(57) **CLAIM**

The ornamental design for a bottle, as shown and described.

DESCRIPTION

FIG. 1 is a perspective view of a bottle showing our new design;

FIG. 2 is a front view thereof;

FIG. 3 is a side view thereof;

FIG. 4 is a top plan view thereof;

FIG. 5 is a bottom plan view thereof;

FIG. 6 is an exploded perspective view thereof; and,

FIG. 7 is an exploded side view thereof, which is rotated

compared to the side view of FIG. 3.

It being understood that the broken lines are for illustrative

purposes only and form no part of claimed design.
